SQUARE HOLDER CLAMP FOR LEVEL OR STRAIGHTEDGE

George Dewey Manville, Rte. 1, Box 526-b, 35520 Oak
Glen Road, Yucaipa, Calif. 92399

Filed May 4, 1967, Ser. No. 6,973

Term of patent 14 years

(Cl. D54—1)

FIG. 1 is a side elevational view of the square holder clamp for level or straightedge showing my new design;
FIG. 2 is an end elevational view thereof;
FIG. 3 is a bottom plan view thereof; and
FIG. 4 is a top plan view thereof; and
FIG. 5 is a perspective view thereof.

The broken line showing is for illustrative purposes only.

I claim:

The ornamental design for a square holder clamp for level or straightedge, substantially as shown and described.
